UNITED STATES PATENT OFFICE.

DAVID L. MASTERS AND JAMES B. COREY, OF BRADDOCK, PENNSYLVANIA.

MEANS FOR APPLYING MOTIVE POWER.

SPECIFICATION forming part of Letters Patent No. 340,229, dated April 20, 1886.

Application filed May 20, 1885. Serial No. 167,123. (No model.)

To all whom it may concern:

Be it known that we, DAVID L. MASTERS and JAMES B. COREY, both of Braddock, in the county of Allegheny and State of Pennsylvania, have invented certain new and useful Improvements in Means for Applying Motive Power Used for Drawing Coal-Cars, Canal-Boats, Ferry-Boats, Street-Railways, &c.; and we do hereby declare the following to be a full, clear, and exact description of the invention, such as will enable others skilled in the art to which it pertains to make and use it, reference being had to the accompanying drawings, which form part of this specification.

15 Our invention relates to an improvement in means for applying motive power, the object being to provide a motive power of simple and durable construction and of small initial cost.

20 Our invention consists in the improved construction and combinations of parts herein-after fully described, and pointed out in the claims.

In the accompanying drawings, Figure 1 is a 25 side elevation of our improved motive power, partly shown in section, the better to illustrate the working parts of our invention. Fig. 2 is an end elevation of the master-wheel, showing the V-shaped recess or channel and 30 gear-wheel combined. Fig. 3 is a cross-section of an open pipe beneath the surface of the ground, in which the cable lies when not in use, and provided with a steam-pipe, to prevent freezing in cold weather. Fig. 4 is a 35 cross-section of a master-wheel, showing an automatic device for clutching the cable when not entirely around the wheel. Fig. 5 is a side view of the same with pulleys at either side, which serve to keep the cable close to 40 the wheel.

To put our invention into practice, we place 45 on a truck, A, mounted on wheels B, an engine and boiler, connected to a shaft, a, on suitable bearings, b. To one end of this shaft a is affixed a small toothed wheel or pinion, c, which meshes with another toothed wheel, d, directly above and secured to a shaft, e, parallel to the line of track f, and placed in bearings g at each end. Each side of the toothed 50 wheel d is provided with conical recesses h, which engage with friction-clutches i k,

mounted on mandrels l l', revolving loosely about the shaft e, on which they are placed. To the friction-clutch i on left of the gear-wheel d is added a bevel gear-wheel, m, which 55 meshes with the bevel-toothed wheel n, forming part of the master-wheel D, placed on a shaft, o, in suitable bearings, p, at right angles to the side of the car A. Around the perimeter of the master-wheel D is a deep 60 V-shaped groove, q, in which is placed a cable, r, having each end securely fastened at widely-separated points. To one end of the mandrel l' is placed a drum, s, mounted on suitable 65 bearings, g, which can be used for lifting heavy 70 bodies. Vertically secured to the frame of the car A is a small threaded shaft, t, on which is a pulley, n, carrying the rope r, which, when revolved, will move to either side of the drum s and prevent climbing of the rope r. 75 To one end of the mandrel l next the front of the car A is secured a bent lever, w, fulcrumed at s below the shaft e, which carries the friction-clutches i k and drum s, and serves to operate the clutches i k.

The cable r when not in use lies in a chamber, y, open at the top, z, and placed beneath the surface of the ground. A steam-pipe, x, is placed within and continues the entire length, and prevents freezing in low temperatures; or we conduct a pipe, x', from the exhaust-chamber of the engine to the open pipe or chamber y beneath.

Figs. 4 and 5 are views of a clutch or grip wheel intended to obviate the necessity of 85 passing the cable r entirely around the master-wheel D, and also facilitate the disconnecting of the car A from the cable r, when desired, without unloosening the cable r at either end.

When desired to put the car A in motion, the engine is started and the lever w is raised, which brings the friction-clutch i in contact with the toothed wheel d and gives it the same speed and motion. The gear-wheel m on the 95 front of the clutch i, meshing with bevel-gearing n on the side of the master-wheel D, rotates the latter, and, acting on the cable r, will move the car A forward.

To bring the drum s in use, the lever w is 100 pressed downward, which separates the front clutch, i, and engages the rear clutch, k, with the

toothed wheel d . The pulley u on the threaded shaft t below distributes the rope r evenly on the drum.

Having thus described our invention, what we claim, and desire to secure by Letters Patent, is—

1. In combination with a pinion, c , secured on a shaft, a , and connected to a motive power, a toothed wheel, d , on each side of which is a deep conical recess, h , the friction - clutches i , k , mandrels l l' , shaft e , lever w , master-wheel D , one side of which is beveled, gearing n , and a cable, r , all constructed and operated as shown and described.

2. In combination with a motive power and car, A , such as described, an open-topped box

or pipe, y , constructed in sections and bolted together, a pipe, x' , leading thereto and connected with the exhaust of the engine placed within the car A , substantially as described. 20

3. In combination with a motive power, truck, or car, A , such as shown and described, a master - wheel, D , about the perimeter of which are placed automatic clutches q' , for gripping the cable r , and pulleys q^2 , for sustaining 25 the rope r a short distance above the lowest point of the wheel, substantially as set forth.

DAVID L. MASTERS.
JAMES B. COREY.
